UNITED STATES PATENT OFFICE.

JAMES W. JOHNSTON, OF SENECA FALLS, NEW YORK.

CONCRETE-FORM ANCHORAGE.

1,176,903.

Specification of Letters Patent. Patented Mar. 28, 1916.

Application filed May 8, 1915. Serial No. 26,877.

To all whom it may concern:

Be it known that I, JAMES W. JOHNSTON, a citizen of the United States of America, residing at Seneca Falls, in the county of 5 Seneca and State of New York, have invented certain new and useful Improvements in Concrete-Form Anchorage, of which the following is a specification, reference being had therein to the accompanying 10 drawing.

This invention relates to a concrete form anchorage and has for its principal object the production of a simple and efficient means for positively retaining the concrete 15 form in its correct set up position while the concrete is being poured therein and while the same is becoming hard.

Another object of this invention is the production of a concrete form anchorage 20 which is so formed as to be carried within the inner portions of the poured concrete after the same has become hard thereby forming a reinforcement for the concrete structure.

25 A still further object of this invention is the production of a concrete form anchorage which is first set up before the concrete is poured into the form and which is then embedded in the concrete for forming 30 a reinforcement therefor, the connecting portions which engage the form being adapted to be removed so as to allow the form to be detachable when necessary.

With these and other objects in view, this 35 invention consists of certain novel combinations, constructions, and arrangements of parts as will be hereinafter fully described and claimed.

In the accompanying drawing: Figure 1 40 is an elevation of a plurality of the form anchors, illustrating the manner in which the same are used. Fig. 2 is a detailed perspective view of the anchor plate, illustrating the manner in which the anchor cable 45 engages the same. Fig. 3 is a detailed perspective view of the anchor rod or frame, showing the anchor cable connected thereto. Fig. 4 is a side elevation of a bolt, illustrating the manner in which the anchor 50 plate is carried thereby, the anchor plate being shown in section. Fig. 5 is a front elevation of the anchor plate mounted upon a bolt.

Referring to the accompanying drawing 55 by numerals it will be seen that the anchor frame is formed of a single rod or strand so

as to form parallel side portions 1 which converge at their lower ends as disclosed at 2, to form the pointed lower end 3. The upper ends of the side portions 1 are bent 60 inwardly as shown at 4 to form the loop 5 which extends into and between the parallel arms or sides 1 as clearly shown in Fig. 3. When in operation a layer of concrete 6 is first poured and at this time a number 65 of the anchor frames may be partially embedded in this concrete 6 as shown in Fig. 1. The upper ends however of the frame each project for a considerable distance above the upper portions of the concrete so as to 70 allow free access to be had thereto. The wooden forms 7 are then set up and a number of bolts 8 may be passed through the forms at any desired height or distance. The anchor plates are then positioned upon 75 the bolts for purposes to be hereinafter set forth. Each anchor plate comprises a body 9 having a central opening 10 through which one of the bolts 8 may pass for the purpose of supporting the anchor plate. A plurality 80 of rearwardly extending wings 11 are formed upon the body 9 while the locking wings 12 extend in the same plane as the body 9. The nut 13 may then be threaded upon the respective bolt until the same engages the body 9. At this time the locking wings 12 may be bent forwardly so as to 85 extend in parallel spaced relation relative to each other and overhang the side portions of the nut 13. In this manner it will be seen 90 that the nut 13 will be positively locked in a set position upon the bolt 8.

An anchor cable 14 is adapted to be used in connection with each anchor plate and frame. This cable has a plurality of loops 95 15 extending from its upper end and these loops are adapted to be passed about the rear portions of the body 9 of the anchor plate. Since the wings 11 extend rearwardly they will prevent the loops from accidentally slipping over the side portions of the anchor plate thereby freeing the anchor plate. As it is now connected to the anchor plate however, the cable will be positively retained in position while the forward ends 100 of the locking wings 12 fitting between the loops 15 as shown in Fig. 2, will hold the loops in spaced relation and will resist any tendency of the anchor plate to have independent rotation upon the bolt. The lower 105 end of the anchor cable 14 is wound around the loop 5 of the anchor frame in any suit-

able manner as disclosed at 16 in Fig 3. This cable when the same is attached to both the anchor plate and the frame will be very taut as shown in Fig. 1 and therefore the 5 forms 7 will be retained in their correct positions. The concrete may then be poured into the form so as to fill the same thereby embedding the anchors within the green concrete. As soon as the concrete has be- 10 come set, the heads 8' of the bolts may be engaged and turned so as to rotate the bolt and cause the same to disengage the particular nut carried thereby. As soon as the bolts have been removed, the forms may 15 then be removed from engagement with the set concrete while the anchor plate, cable, and frame will remain within the interior of the concrete body. Therefore, while the anchor will form a very efficient reinforce- 20 ment for the concrete form, the outer surface of the concrete form will be comparatively smooth as none of the portions of the device will project through or even to the outer surface of the concrete structure. 25 It is of course obvious that any shaped form may be used in connection with this device as it is not intended to limit the use thereof to the specific form shown in the accompanying drawing. 30 From the foregoing description it will be seen that a very durable and efficient anchor has been provided for concrete forms which may be very readily set up so as to retain the form in its correct position and prevent 35 the same from bulging or springing when the concrete is being poured thereinto and which will form an efficient reinforcing member for the concrete, after the form has been removed. 40 What I claim is: 1. A concrete form anchorage comprising a cable, an anchor frame carried by said cable, an anchor plate carried by said cable and adapted to be detachably connected to a 45 form wall, said frame being adapted to be first embedded in cement whereby the form wall may be entirely filled with concrete, said cable, plate, and frame constituting a reinforcement for the concrete structure, 50 after the form has been removed. 2. In a device of the class described, the combination of an anchor cable, means carried by one end of said cable for detachably retaining a concrete form in a set up position, means carried by the opposite end of 55 said cable for engaging a supporting element for holding the cable taut, said cable and said means being adapted to be embedded in the concrete for forming a reinforce- 60 ing element therefor.

3. In a device of the class described, the combination of an anchor frame, said frame formed from a single strand of material, a cable attached to said frame, means carried by said cable for detachably engaging and 65 retaining a concrete form in a set up position, said cable, means, and frame constituting a reinforcement for the cement, after the form has been removed.

4. In a device of the class described the 70 combination of an anchor plate, said anchor plate having a body with a central opening, rearwardly extending wings formed upon said body, a bolt extending through the opening formed in said bcdy, said bolt being 75 adapted to pass through a concrete form, a nut carried by the inner end of said bolt and bearing upon said body, locking wings formed upon said bcdy and extending in parallel spaced relation to each other so as 80 to form a lock for said nut, an anchor cable extending around said body, said rear- wardly extending wings constituting means for preventing the displacement of said cable, means for anchoring the lower end of 85 said cable whereby a concrete form will be held in its correct position, said plate, cable, and means being adapted to be embedded in cement for forming a reinforcement there- 90 for, said bolt being adapted to be removed 95 from engagement with said nut, when the concrete has become set, whereby the form may be removed.

5. In a device of the class described, the 95 combination of an anchor frame, said anchor frame formed from a single strand of metal so as to provide parallel side por- 100 tions, said side portions provided with an integral loop extending therebetween, the opposite end of said side portions termi- 105 nating in a pointed lower structure whereby the frame may be easily forced into an inclosing plastic medium, an anchor cable attached to said loop, means engaging the opposite end of said anchor cable for retaining the same in detachable engagement with a concrete form whereby said form may be retained in its correct position while the concrete is setting, said means being adapted to release said form when necessary, and 110 said cable, frame, and means constituting a reinforcement for the concrete structure when set.

In testimony whereof I hereunto affix my signature in presence of two witnesses.

JAMES W. JOHNSTON.
